TOY BALLOON SPACE KITE

Robert A. Wolfe, 455 Elizabeth Ave., Newark, N.J.

Filed Apr. 17, 1964, Ser. No. 79,542

Term of patent 14 years

(Cl. D34—15)

FIG. 2.

FIG. 3.

FIG. 1 is a front elevation of a toy balloon space kite showing my new design; and

FIG. 2 is a rear elevational view of the toy balloon space kite of FIG. 1; and

FIG. 3 is a side elevational view of the toy balloon space kite of FIGS. 1 and 2.

I claim:

The ornamental design for a toy balloon space kite, as shown.
